COMPRESSOR

William W. Wishart, Chicago, Ill.

Application June 8, 1940, Serial No. 339,478

6 Claims. (Cl. 230—154)

This invention relates to improvements in compressors and more particularly to air compressors employed in connection with air tanks wherein it is desired to store air under a predetermined pressure.

It is an object of this invention to provide an air compressor of the rotary type, including few parts that may be readily assembled and in which the rotor may be adjusted within the stator without taking down the assembly. It is another object of this invention to provide a rotary compressor in which the direction of rotation of the rotor may be readily reversed by a few simple adjustments and in which forced lubrication is affected without the use of an oil pump. It is also an object of this invention to provide an automatic suction valve cooperating with the pressure side of the compressor to allow the rotor to idle when the desired pressure is reached in the air tank and to cause the rotor to operate as soon as the pressure in the tank descends below the predetermined degree. It is also an object of this invention to so locate the discharge ports of the stator that the air passes therethrough in the direction of rotation of the rotor and thereby provides an improved form of oil separator. It is a further object of this invention to provide means for cooling the oil used in the forced lubrication system.

With these and other objects in view, reference is made to the accompanying sheets of drawings which illustrate a preferred form of this invention with the understanding that minor changes may be made without departing from the scope thereof.

In the drawings:

Figure 1 is a top plan view of a preferred form of this air compressor with parts of the automatic valves shown in horizontal section.

Figure 2 is a view in vertical transverse section taken on the line 2—2, Figure 1, looking in the direction of the arrows, showing the oil tank in elevation.

Figure 3 is a view in vertical longitudinal section taken on the line 3—3, Figure 1, looking in the direction of the arrows, showing the air strainer, automatic valve, and cooling pipes in elevation.

Figure 4 is a view in vertical section taken on the line 4—4, Figure 1, looking in the direction of the arrows.

Figure 5 is a view partly in vertical transverse section taken on the line 5—5, Figure 3, looking in the direction of the arrows, and partly in end elevation.

Figure 6 is a fragmentary view in vertical transverse section taken on the line 6—6, Figure 3, looking in the direction of the arrows.

Figure 7 is a view partly in section and partly in elevation taken on the line 7—7, Figure 6, looking in the direction of the arrows.

Figure 8 is a fragmentary view in horizontal section taken on the line 8—8, Figure 5, looking in the direction of the arrows.

Figure 9 is a fragmentary view of the end plate partly in elevation and partly in section, illustrating the air intake duct, showing the rotor reversed in direction of rotation.

Figure 10 is a fragmentary view in horizontal section taken on the line 10—10, Figure 9, looking in the direction of the arrows.

Figure 11 is a fragmentary view partly in end elevation and partly in section of a modified form of air intake valve and air intake duct.

Figure 12 is a similar view, illustrating a change in the direction of the flow of the air from the intake valve when the direction of rotation of the rotor is reversed.

Figure 13 is a fragmentary plan view of the gasket interposed between the air intake valve and end plate, as indicated by the line 13—13, Figure 12, looking in the direction of the arrows.

The air compressor constructed in accordance with this invention and in the preferred form illustrated upon the drawings includes a rotor 1 mounted eccentrically within a cylindrical stator 2 supported between end plates 3 and 4. The end plate 4 is of less area than the end plate 3 and is secured thereto by threaded bolts 5 passing through end plates 4 and 3 with the securing nuts 6 on the exterior side of the end plate 3. The end plate 3 also supports a cylindrical air-tight casing 7 enclosing the stator 2 and end plate 4. A driving shaft 8 passes through openings provided therefor in end plate 3, rotor 1, and end plate 4 and is connected to the rotor 1 by a key 9 received in a keyway 10 in the rotor 1, which key is terminated short of the bottom of the keyway 10, as shown in Figure 3. The end plate 3 is provided with an outwardly extending recessed boss 11 for receiving a ball bearing of any desired form for the driving shaft and a shaft seal preferably of the form disclosed in this applicant's prior Patent No. 2,140,304 of December 13, 1938. The end plate 4 is provided with a recessed boss 12 for receiving a ball bearing of any desired form for the end of the driving shaft 8 and is provided with a cover plate 13 secured thereover similarly to the cover plate 14 upon the boss 11. If desired, the driving shaft

2 may be provided with an offset pulley 15 at its exterior end for transmitting power to rotate the shaft.

The casing 1 is preferably secured in air-tight relation by tap screws 16 to that side of the end plate 3 in engagement with the stator 2 so that all of the working parts of the compressor are contained within the casing 1 and are carried by the end plate 3. By this construction, the stator 2 may be a section of steel tubing. As shown in Figure 6, it is preferable to employ five bolts for securing the rotor and stator between the end plates 3 and 4, two of which are arranged on either side of the axis of the stator at the bottom to support the stator in its proper position and one is arranged to engage in a groove 17 in the upper surface of the stator to maintain its fixed relation to the end plates. By providing a little play in the end plates 3 and 4 about the bolts 5, slight adjustments may be made between the rotor and stator by loosening the nuts 6, making the adjustment, and then tightening the nuts 6, all without taking down the assembled parts.

The rotor 1 mounts a plurality of spaced-apart pistons 18 within apertures 19 provided therefor in the circumference of the rotor. One end of each piston is pivotally mounted in the body of the rotor and the outer surface of the piston is formed on an arc concentric with the rotor so that as the rotor passes the point of tangential contact with the inner walls of the stator, the outer surface of the piston will act as a continuation of the rotor surface. As the rotor passes beyond this point, centrifugal force will cause the outer surface of the piston to continue to wipe over the inner surface of the stator and the free end will form an abutment and compress the air in front of it between the inner surface of the stator and the surface of the rotor. The inner end of this abutment is formed so that in the most extended position of the piston, the air compressed in advance of the abutment will enter the recesses 19 in the rotor and will assist the centrifugal force in holding the piston in engagement with the walls of the rotor.

As shown in Figures 5 and 6, the rotor moves in a clockwise direction with the center of rotation of the rotor above the axis of the stator and provision is made to admit atmospheric air into the space between the outer surface of the rotor and inner surface of the stator through a port 20 below and to the right of the centers thereof and the air compressed between pistons is discharged through a plurality of discharge ports 21 in the stator preferably diametrically opposite the air inlet port. The air intake port 20 is formed in the end plate 3 so that atmospheric air is admitted to the space between the rotor and stator at right angles to the direction of rotation of the rotor. The connection between the air intake port 20 and the atmospheric air will hereinafter be described. This invention contemplates the provision of a plurality of similar spaced apart discharge ports 21 arranged parallel to each other which pass at an angle through the body of the stator so that the centers of the openings of the ports on each side of the stator lie in planes parallel to the axis of the stator, and it is preferable to construct the ports so that the longitudinal center line of the inner surface first wiped over by a piston will be in a plane approximately tangential to the rotor, as shown in Figures 6 and 7, so that the air under pressure is caused to flow through the walls of the stator in the direction of the movement of the pistons 70

and is discharged into the space within the cylindrical casing 1 which surrounds the stator 2 and end plate 3.

It is preferable to provide the end plate 3 with a vertical boss 22 to contain a vertical air duct 23 communicating with the air intake port 20 in the end plate 3 at the bottom and opening through a horizontal support 24 preferably formed integral with the top of the end plate 3 to communicate with an automatic valve casing 25 mounted thereon. The valve casing 25 is mounted on a base plate 26 and contains two spaced apart chambers 27 and 28 preferably closed by closure plates 29 and 30. The larger chamber 27 at the end opposite the closure plate 29 communicates by an axial duct 31 to a vertical passage 32 which is extended through the base plate 26 to register with the upper opening of the air duct 23. This chamber adjacent the end provided with the axial duct 31 is also provided upon its upper side with a passage 33 to communicate with an air strainer 34 of commercial type which is supported in the boss 35 formed integral with the casing 25. The chamber 27 is provided with a piston 36 having an axial projection 37 adapted to seat upon the duct 31 but is normally maintained unseated by a coil spring 38 interposed between the end of the chamber 27 and the piston 36.

Upon rotation of the rotor 1 air is then drawn in through the air strainer 34, passage 33, through the chamber 27 and duct 31 into the passage 32 registering with the air duct 23 to the air intake port 20 in the end plate 3 and the air within the stator is discharged under pressure through the discharge ports 21 into the interior of the casing 1. The air under pressure is discharged from the casing 1 through a check valve 39 mounted in a valve casing 40 carried upon the exterior of the casing 1 and communicating with the interior thereof through the duct 41. The other end of the check valve casing is connected to a pipe 42 leading to an air tank or other instrumentality where air under pressure is desired.

When the predetermined pressure within the air tank, not shown, is reached, in order that the rotor may idle it is necessary to close the intake side of the compressor to the atmosphere and at the same time, relieve the accumulated pressure within the casing 1. In order to accomplish this the piston 36 is provided with an axial projection 43 which will engage the end plate 29 of the cylinder 27 under the tension of the spring 38 when the duct 31 is uncovered to allow that end of the piston to uncover the opening of a duct 44 passing through the valve casing 25 to communicate with the smaller chamber 28. The smaller chamber 28 mounts a piston 45 having a piston rod 46 passing through a perforated closure plate 47 for the end of the cylinder opposite the closure plate 30, which piston rod is secured to the closed end of a normally contracted metallic bellows or Sylphon 48 mounted in a bracket 49 carried upon the base plate 26 so that upon expansion and contraction of the Sylphon 48 the piston 45 will be reciprocated. The piston 45 is provided with an annular groove 50 which is adapted to register with the passageway 44 in the casing 25 when the Sylphon has been expanded to move the piston to the end of its travel in the direction of the end plate 30 and at the same time, to register with a passageway 51 opening through the side wall of the valve casing 25. This passageway 51 is in communication with a pipe 52 which joins a T-connection 53, the other arm of which is

connected by a pipe 54 to the interior of the Sylphon 48. The leg of the T-connection is joined to a pipe 55. It is preferable to connect the check valve casing 40 upon the cylindrical casing 7 of the compressor to the air tank or other disposition of the air under pressure through the pipe 42 by a T-connection 56 and the pipe 55 is joined to the T-connection so that when the predetermined pressure is reached the additional pressure passing through the T-connection 56 upon the check valve casing 40 and pipe 55 will follow through the T-connection 53 and pipe 54 to the interior of the Sylphon which will cause it to expand and move the piston 45 to the end of its travel to cause the annular groove 50 therein to register with the air passages 51 and 44 in the valve casing 25 so that the pressure will be transmitted from the T-connection 53 through pipe 52, passageway 51, chamber 28, passageway 44 to the rear of the end of piston 36 within the chamber 27 which will move the piston against the tension of the spring 38 to cause the projection 37 to seat upon the duct 31 and close the passageway 32 to the atmosphere through the air strainer. In order to relieve the pressure within the casing 7, an annular groove 57 is provided in the piston 36 and so arranged that when the increased pressure has seated the extension of the piston 37 about the duct 31 the annular groove will communicate with a passageway 58 in the side of the valve casing 25 and at the same time, communicate with a duct 59 in the wall of the valve casing 25 which passes below the chamber 28 to communicate with a pipe 60 which passes through a connection 61 on the side of the casing 7 so that the pressure within the casing 7 may be equalized through the pipe 60, duct 59, annular groove 57 in the piston 36, and pass to the atmosphere through the passageway 58, as shown in Figure 4, whereupon the rotor may idle.

In order to adjust the pressure required to expand the Sylphon 48 a coil spring 62 is interposed between the end of the Sylphon 48 in engagement with the piston rod 46 and an adjustable abutment 63 mounted in a bracket 64 carried on the base plate 26. This adjustable abutment 63 is in the form of an exteriorly screw-threaded cylindrical member through which the piston rod 46 passes and is provided with a knurled head 65 and the interior of the bracket 64 is correspondingly screw-threaded to engage the threads on the abutment whereby the rotation of the knurled head 65 will advance or retract the abutment to increase or decrease the tension of the spring 62.

When the pressure recedes below the predetermined amount, the spring 62 will act upon the Sylphon 48 to retract the piston 45 to the other end of its travel and in so doing, will cause the end of the piston 45 to uncover the passageway 44 and close the passageway 51. The end plate 30 is provided with an axial passageway 30^a so that when the piston 45 is in the position shown in Figure 1 and the spring 38 unseats the duct 31 the air between the end of the piston 36 and the end plate 29 will pass through the duct 44 into the chamber 28 and bleed out through the axial passageway 30^a.

The provision of the discharge ports 21 through the walls of the stator 2 and the manner of mounting the stator and rotor upon the end plate 3 allow a reversal of the movement of the rotor with but few adjustments. As shown in Figures 3, 5 and 6, the rotor is rotated in a clock-

wise direction. The rotor may be mounted to rotate in counter-clockwise direction by removing the casing 7 from the end plate 3 and then removing the bolts 5 and end plate 4. The rotor and stator are then removed from the shaft 8 and replaced in reverse position thereon and the parts reassembled. However, provision must be made for the atmospheric air to be delivered to the space between the rotor and stator through a port on the opposite side of the vertical center from the intake port 20. Provision for this is made by forming a horizontal boss 66 upon the exterior of the end plate extending from the bottom of the boss 22 to contain a similar air passage 67 which is shown in Figure 3 as joining the passageway 23. As shown in Figure 8, an intake port 68 is formed in the end plate 3 communicating with the horizontal passage 67 in the proper relation to allow air to pass therethrough when the rotor is rotated in a counter-clockwise direction. Figures 3 and 8 show openings formed in the apex of the bosses 22 and 66 and in the horizontal boss 66 opposite the intake ports 20 and 68, which openings are closed by threaded closure members 69 and 70. When the rotor is positioned to rotate in a clockwise direction the closure 70 which is provided with an extension plug 71 adapted to close the intake port is inserted through the opening in the boss to seal the intake port 68 while the closure 69 merely closes the opening in the boss. When the rotor has been positioned to rotate in a counter-clockwise direction these closures 69 and 70 are reversed, as shown in Figure 10, so that the intake port 20 is sealed and the air intake port 68 is open to communicate with the atmosphere through air passages 67 and 23, as shown in Figure 9.

While this manner of reversing the flow of atmospheric air to the interior of the stator is illustrated in connection with Figures 1, 3 and 5 of the drawings whereby the change of flow of air is regulated by the position of the plug 68, yet the same result may be accomplished in a slightly different manner as shown in Figures 11, 12 and 13. Figure 11 shows two vertical bosses on the end plate 3, one boss 22 forming the vertical air duct 23 the same as in Figure 3 and a similar boss 72 forming a similar air duct 73 arranged on the other side of the vertical center of the rotor. The air duct 23 communicates with the air intake port 20 and the air duct 73 communicates with the air intake port 68. In this figure, the rotor is shown in dotted lines as rotating in a clockwise direction and the automatic suction or intake valve casing 25 is mounted on the base plate 26 so that the air passage 32 in the valve casing 33 opens above the axis of the rotor. The base plate 26 is spaced apart from the support 24 of the end plate 3 by a gasket 74 which is provided with an elongated longitudinal slot 75 so arranged that when secured between the support 24 and base plate 26 by the tap screws 76 the slot 75 will form a means of communication between the air passage 32 in the valve casing 25 and the air duct 23, as shown in Figure 11. In this form of construction, when it is desired to reverse the flow of air when the rotation of the rotor is reversed the base plate 26 is detached and the gasket is reversed, as shown in Figure 12, and the base plate again secured, whereupon the flow of air will be directed into the air duct 73 when the rotor rotates in counter-clockwise direction.

This invention contemplates lubricating the moving parts of the compressor by providing an

axial opening 77 in the cover plate 13 for the bearing of the shaft 8 in the end plate 4 and by providing an axial duct 78 in that end of the shaft connected with a radial duct 79 opening through the circumference of the shaft 8 into the keyway 10 of the rotor 1. It is preferable to provide recesses 80 and 81 in the ends of the rotor 1 about the shaft 8. A bath of oil or other lubricant is introduced into the casing 7 which will surround the stator 2 and end plate 4, which bath is maintained at a normal level so that the pressure created within the casing 7 will force the oil through the axial opening 77 to lubricate the bearings of the shaft 8 behind the cover plate 13, enter the axial duct 78 in the shaft 8, pass through the radial duct 79 through keyway 10, and then into the recesses 80 and 81 to lubricate the ends of the rotor 1 in wiping over the end plates 3 and 4 and from the recess 81 in the end of the rotor 1 to lubricate the bearings of the shaft 8 in the boss 11. The lubricant will be prevented from escaping from the boss 11 by the seal arranged about the shaft 8. As the pistons 18 traverse the circumference of the rotor 1, the pivoted portions thereof will be lubricated by the oil forced between the ends of the rotor and the end plates 3 and 4.

The lubricant or oil is supplied to the interior of the casing 7 from an oil cup or reservoir 82 mounted upon the upper surface of the casing 7 and communicating with the interior thereof by a pipe 83 terminating just below the axial opening 77 in the cover plate 13. The cup or reservoir 82 is provided with a sealed cover 84 and the opening of the cup into the pipe 83 is provided with a spring-pressed valve 85 which normally acts to close the opening. The cover 84 is provided with a screw plug 86 in axial alignment with the oil pipe 83 and is provided with an axial depending post 87 so arranged to depress the stem 88 of the valve 85 when the plug 86 is seated in the cover 84 to allow oil to flow as needed into the casing 7 and maintain the level of the oil bath for the proper lubrication of the moving parts, so that oil may be poured into the cup 82 through the opening in the cover when the plug 86 is removed.

It has been found that when air under pressure containing particles of oil in suspension impinges upon polished surfaces such as chromium-plated metal, the oil will be separated therefrom and will drain off the polished surface. By arranging the discharge ports 21 of the compressor in the walls of the stator 2, it is possible to provide a baffle of polished or chromium-plated metal in the path of the air under pressure as it leaves the discharge ports 21. As shown in Figures 5, 6 and 7, it is preferable to provide a baffle 89 in the form of a curved plate extending transversely of the stator 2 above the discharge openings 21 with its furthest edge secured to the outer surface of the stator 2 and with its inner surface polished or chromium-plated so that any particles of oil carried over in suspension with the air discharged from within the stator 2 will impinge upon the underside of the baffle 89 and be separated from the air and the separated oil will drain from the baffle 89 into the oil bath surrounding the stator 2 and end plate 4 within the casing 7.

As this oil or other lubricant is being continually used over and over again to lubricate the moving parts of the compressor, it is desirable to prevent the temperature of the oil bath from being raised beyond a predetermined degree. This invention contemplates the provision of a cooling coil 90 within the casing 7 immersed in the oil bath contained therein. As shown in Figure 3, the intake 91 and exhaust 92 of the cooling coil

are each passed through apertures provided therefor in the end of the casing 7, which apertures are provided with seals 93 and sealing plugs 94. The cooling coil may act to circulate a cooling fluid of either liquid or air as may be desired, and the cooling fluid may be circulated through the coil in any desired manner and therefore, this means is not illustrated upon the drawing.

By the construction contemplated and above described, it is readily seen that the compressor may be assembled at the factory to provide either a clockwise or a counterclockwise rotation to the rotor and the direction of rotation of the rotor may be readily and easily changed in the field.

Likewise, it is obvious that, if desired, the top of the support 24 may be recessed to connect the passage 32 in the suction valve casing 25 to both of the air ducts 23 and 73 and the bosses 22 and 72 provided with openings aligned with the intake ports 20 and 68 to be closed with closures 69 and 70 in the manner described and shown in Figures 8, 9 and 10, in lieu of the gasket 74 having the slot 75, and thereby avoids the necessity of removing the base plate 26 of the valve casing 25 as described and shown in Figures 11 and 12.

It is also obvious that, if desired, reciprocating vanes may be substituted in the rotor for the centrifugally operated pistons 18 without departing from the scope of this invention.

It is to be noted that the bath of the lubricant in the casing 7 is maintained at a level to be forced by the air under pressure within the casing 7 through the opening 77 in the end plate 13 by terminating the lubricant supply pipe 83 just below the desired level whereby whenever the lubricant uncovers the opening 77 the lubricant will flow from the reservoir 82 through the pipe 83 until the level of the bath again seals the open end of the supply pipe.

What I claim is:

1. A rotary compressor including a driving shaft, a rotor mounted thereon, a cylindrical stator surrounding the rotor, an end plate having a bearing and a seal through which the shaft passes, a second smaller end plate provided with a bearing to receive one end of the shaft, an air-tight casing secured to the first end plate surrounding in spaced apart relation the stator and smaller end plate, means for assembling the rotor and stator between the end plates passing through the first end plate to engage the second end plate, said means also supporting the stator, and means upon the first end plate cooperating with similar means upon the second end plate for adjusting the relation of the stator to the rotor without removing the air-tight casing wherein the said assembly means includes bolts passing through both end plates, some of said bolts supporting the stator thereon; nuts threaded upon the ends of the bolts upon the exterior of the first end plate, and wherein the adjusting means includes the provision of sufficient clearance about the bolts in the end plates to accomplish the adjustment.

2. A rotary air compressor including a rotor, a cylindrical stator surrounding the rotor said rotor having a plurality of pivotally mounted centrifugally operated pistons contained in recesses in the rotor with free ends impinging upon the inner surfaces of the stator to form compression abutments, and end plate having an air-tight casing secured thereto embracing said stator, a second smaller end plate within and spaced apart from the casing, detachable

means assembling the smaller end plate, rotor and stator upon the first end plate, an air intake port in the first end plate to admit air into the stator, a second normally closed air intake port in the first end plate equally spaced apart from the vertical center line of said end plate and on the side of the center line opposite the first intake port, and a plurality of discharge ports in the wall of the stator above the said air intake ports, whereby the rotor and stator may be removed from between the end plates, reversed and reassembled and upon removing the closure of the second air intake port and closing the first air intake port the compressor will operate with the rotor rotating in a reversed direction.

3. The structure of claim 2, wherein the detachable assembly means includes a plurality of bolts passing between the end plates about the exterior of the stator, two of which are positioned to support the stator in proper relation to the air intake ports in the end plate, and a third bolt passing through a groove in the outer surface of the stator midway between the stator supporting bolts to insure the passage of air through one of the intake ports depending upon of the direction of rotation of the rotor by aligning the air intake ports with the interior of the stator.

4. The structure of claim 2, wherein the first intake port is connected by an air duct formed in the first end plate to an air inlet valve, and wherein said air duct is continued to the second normally closed air intake port.

5. The structure of claim 2, wherein the first

intake port is connected by an air duct formed in the first end plate to an air inlet valve, and wherein said air duct is continued to the second normally closed air intake port, and wherein the end plate is perforated in alignment with the first intake port and perforated in alignment with the second intake port, said perforations adapted to be closed by similar plugs threaded thereinto, one of said plugs provided with an extension adapted to close and seal the oppositely disposed air intake port.

6. A rotary compressor including a driving shaft, a rotor mounted thereon, a cylindrical stator surrounding the rotor, an end plate having a bearing and a seal through which one end of the shaft passes, a second smaller end plate provided with a bearing to receive the other end of the shaft, an air-tight casing secured to the first end plate surrounding in spaced apart relation the stator and smaller end plate, means for assembling the rotor, stator and smaller end plate upon the first end plate, an air intake port in the first end plate, air discharge ports in the wall of the stator between the end plates, a lubricating system for the moving parts of the compressor, and an oil separator upon the exterior of the stator including a curved plate mounted transverse of the stator presenting its concave surface to the discharge ports, said concave portion having a highly polished surface whereby the particles of lubricant separated from the air upon striking the separator will quickly drain therefrom.

WILLIAM W. WISHART.
